STRAINER

Roy F. Broyhill, Dakota City, Nebr. 68731

Filed Aug. 6, 1969, Ser. No. 18,566

Term of patent 14 years

Int. Cl. D23—01

U.S. Cl. D23—4

FIG. 1

FIG. 2

FIG. 3

FIG. 5

FIG. 4

FIG. 1 is a perspective view of a strainer showing my new design,

FIG. 2 is an elevational view thereof from a position approximately ninety degrees to the right of FIG. 1,

FIG. 3 is a top view thereof,

FIG. 4 is a bottom view thereof, and

FIG. 5 is a bottom view showing a second embodiment thereof.

I claim:

The ornamental design for a strainer, as shown and described.
